BLAKE TAYLOR, OF PINEVILLE, WEST VIRGINIA.

FORM FOR CONCRETE CULVERTS.

1,238,456.

Specification of Letters Patent. Patented Aug. 28, 1917.

Application filed March 6, 1917. Serial No. 152,569.

To all whom it may concern:

Be it known that I, BLAKE TAYLOR, a citizen of the United States of America, and resident of Pineville, county of Wyoming, 5 and State of West Virginia, have invented certain new and useful Improvements in Forms for Concrete Culverts, of which the following is a specification.

This invention relates broadly to culvert 10 forms, and more particularly to a form for concrete culverts and to the method of employing the same.

The primary object of the invention is to provide a simple and comparatively inexpensive 15 culvert form which not only permits of the building of the culvert in sections, or as conditions may render expedient, but which also permits of the construction of the upper and lower halves separately, or at 20 different times, having in view to facilitate the work and to reduce the labor and expense of construction to a minimum.

A further object is to provide a form for use in culvert construction, a part or all of 25 which may become a permanent part of the completed structure, it being so inexpensively made that the salvage value of the parts not readily recoverable is insufficient to justify the time and labor necessary to effect 30 their removal.

With these and other important objects in view, the invention resides in the features of construction, arrangement of parts, and combinations of elements and method of 35 using which will hereinafter be fully described, reference being had to the accompany drawings, in which—

Figure 1 is a perspective view of the invention, showing successive stages in the 40 construction of a culvert;

Fig. 2 is a cross section of the invention, showing the lower half of a culvert completed;

Fig. 3 is an enlarged detail view showing 45 a portion of the upper half of the form; and—

Fig. 4 is an enlarged detail perspective view, partly in section, showing a spacing block.

50 In constructing a culvert in accordance with my invention, two separate form sec-

tions are employed, one being a bottom section and the other a top section. The bottom section is used as a support for the lower half or section of the culvert proper, 55 which is formed not only prior to the formation of the upper half or section of the culvert, but also prior to building up the top section of the form. The bottom form-section is preferably of semi-cylindrical form 60 and is designed to serve as a support for the concrete of the lower culvert-section which is poured or otherwise suitably applied, as by a cement gun to the upper, or interior, face thereof; and the top form-section, 65 which is also preferably of semi-cylindrical form, is designed to serve as a support for the concrete of the upper culvert-section which is applied to the upper, or exterior, face thereof. The said top form-section is 70 of such relatively smaller size—that is, is constructed upon a radius of such relatively less length—than the bottom form-section that the upper culvert-section formed on the former has the same cross sectional dimensions as those of the lower culvert-section formed on the latter, thus providing for 75 the union of the upper and lower culvert-sections in a one-piece culvert body of regular shape or curvature throughout. 80

In the drawings, 1 indicates the bottom form-section which may be constructed of any suitable material, preferably wooden boards laid lengthwise edge to edge and having a substantially semi-cylindrical 85 trough shape, the same being mounted upon and supported by the lower sections 2 of properly shaped form templets composed of appropriate material, which templets are disposed in alinement and are located at 90 appropriately spaced intervals. Rigidly mounted upon the upper, or interior, face of said form section 1 is a plurality of suitably located lugs or supports 3 which have notches or recesses 4 formed in the lateral 95 edges thereof designed for the reception in seated position of metal rods 4, preferably arranged in interlaced relation, which are designed to be embedded in and to constitute a reinforcement for the concrete 100 composing the lower culvert-section 5, said concrete being spread to a substantially even

depth over the interior surface of said form section 1.

Each of the lower templet-sections 2 carries thereon at each of its opposite ends an upright arm or post 6 designed for having rigidly attached thereto the opposite ends of upper templet-sections 7 which are disposed in reversed relation to said templet-sections 2. In practice, said sections 7 are mounted 10 in place subsequent to the formation, as hereinbefore described, of the bottom culvert-section. The curved surface of said section 7 is formed with a radius substantially equal to that of the inner surface of 15 the form-section 1, so that the outer surface of the top culvert-section 8 which is gaged thereby will be accurately coextensive with the outer, or under, surface of the lower culvert-section 5 formed on the bottom 20 form-section 1.

The top form-section 9 which is also composed of boards disposed lengthwise has its exterior, or upper, surface in the arc of a circle whose radius is substantially the same 25 as that of the interior of the lower culvert-section 5. Said section 9 has mounted on its exterior surface at properly spaced intervals a series of lugs 10 similar to the lugs 3, hereinbefore mentioned, which serve as 30 supports for a suitable reinforcement composed of rods 11 or the like. Some of said lugs, as 10^a, serve as space-blocks whereby said top form-section 9 is held at a spaced 35 distance from the upper templet-section 7, such lugs being disposed between the latter and said form-section 9, as shown in Figs. 1, 2 and 3.

Said form-section 9 has its component 40 boards loosely seated upon underlying shape maintaining supports disposed at points adjacent to the positions occupied by the templets, each support being composed of a plurality of centering pieces, or frame members, 12 which, together with said form-section 45 9, are suspended from the upper templet-section, as by means of wires 13. Said frame members 12 are pivotally connected at their adjacent ends, as upon withdrawable pivot nails 14.

50 When the top form-section has been mounted, as aforesaid, concrete is spread thereon, preferably by means of a cement gun to form the upper culvert section 8. As is obvious, the space between the top form-section and the upper templet-section is of 55 the proper thickness desired for the upper culvert-section and constitutes a guide or gage in the application of the concrete.

It will be evident that the top form section 60 may be collapsed by cutting the supporting wires 13, after which it may be readily removed if desired, it being understood that when said wires are cut the frame members 12 relatively move inward on their

65 pivot pins 14, permitting the boards of the overlying form-section to separate and fall inward. It will also be obvious that the upper templet-sections may be removed 70 without difficulty, thus leaving unrecoverable only the lower templet-sections and the bottom form-sections.

In practice, the work of constructing the lower half of the culvert is completed for a 75 distance in advance of that of constructing the upper half.

What is claimed is—

1. A form for concrete culverts and the like, comprising upper and lower templet-sections adapted to be rigidly connected in superposed relation, a bottom form section 80 of substantially semi-circular shape mounted upon the lower of said templet sections, and a top form-section suspended from said upper templet-section at a spaced distance from the latter, said top form-section having its 85 outer surface in the extended curvilinear surface of the interior of the concrete applied to said bottom form-section.

2. A form for concrete culverts and the like, comprising upper and lower templet-sections adapted to be rigidly connected in superposed relation, a bottom form section 90 of substantially semi-circular shape mounted upon the lower of said templet sections, and a top form-section suspended from said upper templet-section, said upper templet-section having its lower edge or face in the extended curvilinear surface of the interior of said bottom form-section, and said top form-section being spaced from said edge or face 95 a distance approximating the desired thickness of concrete to be applied thereto.

3. A form for concrete culverts and the like, comprising a templet-section, a bottom form-section mounted upon said templet-section, a second templet-section adapted to be superposed upon the first-mentioned templet-section subsequent to the application of the concrete to said bottom form-section, a top form-section complementary to said bottom form-section and spaced from the extended curvilinear surface of the interior of the latter a distance substantially equal to the thickness of the cement applied to the latter, said top form-section being suspended 105 from said upper templet-section, said upper templet-section having its lower edge or face curved to correspond with the curvature of the interior surface of the bottom-form section and in the extended curvilinear surface 110 of the interior of said bottom form-section, and means whereby said top form-section is 115 suspended.

4. A form for concrete culverts and the like, comprising bottom and top form-sections, each of substantially semi-circular form, designed to have concrete applied 125 respectively to their interior and exterior sur-

faces at separate and distinct steps in the construction of the culvert, said form-sections being of such relative sizes that the concrete applied to the top form-section accurately registers and forms a union with that applied to the bottom form-section, and superposed templet-sections forming supports for said form-sections.

In testimony whereof, I affix my signature in presence of two subscribing witnesses.

BLAKE TAYLOR.
